US00D536450S

(12) **United States Design Patent** (10) **Patent No.:** **US D536,450 S**
(45) **Date of Patent:** **** Feb. 6, 2007**

(54) **APPLICATOR FOR USE WITH
ELECTROTHERAPY AND/OR ULTRASOUND
THERAPY PRODUCT**

(75) Inventor: **Bradley Peter Ryan**, Sydney (AU)

(73) Assignee: **Encore Medical Alert Corporation**,
Henderson, NV (US)

(**) Term: **14 Years**

(21) Appl. No.: **29/192,463**

(22) Filed: **Oct. 27, 2003**

(51) **LOC (8) Cl.** **24-02**

(52) **U.S. Cl.** **D24/144**

(58) **Field of Classification Search** D24/144,
D24/211, 200, 214, 215, 170; 601/6, 15,
601/71, 73; 606/41; 607/2, 115

See application file for complete search history.

(57) **CLAIM**

The ornamental design for an applicator for use with electrotherapy and/or ultrasound therapy product, as shown.

DESCRIPTION

FIG. 1 is a perspective view of the first embodiment of the applicator of my new design.

FIG. 2 is a front view of the first embodiment of the applicator of my new design.

FIG. 3 is a right side view of the first embodiment of the applicator of my new design. The left side view is a mirror image of FIG. 3.

FIG. 4 is a rear view of the first embodiment of the applicator of my new design.

FIG. 5 is a top view of the first embodiment of the applicator of my new design.

FIG. 6 is a bottom view of the first embodiment of the applicator of my new design.

FIG. 7 is a perspective view of the second embodiment of the applicator of my new design.

FIG. 8 is a front view of the second embodiment of the applicator of my new design.

FIG. 9 is a right side view of the second embodiment of the applicator of my new design. The left side view is a mirror image of FIG. 9.

FIG. 10 is a rear view of the second embodiment of the applicator of my new design.

FIG. 11 is a top view of the second embodiment of the applicator of my new design.

FIG. 12 is a bottom view of the second embodiment of the applicator of my new design.

FIG. 13 is a perspective view of the third embodiment of the applicator of my new design.

FIG. 14 is a front view of the third embodiment of the applicator of my new design.

FIG. 15 is a right side view of the third embodiment of the applicator of my new design. The left side view is a mirror image of FIG. 15.

FIG. 16 is a rear view of the third embodiment of the applicator of my new design.

FIG. 17 is a top view of the third embodiment of the applicator of my new design.

FIG. 18 is a bottom view of the third embodiment of the applicator of my new design.

FIG. 19 is a perspective view of the fourth embodiment of the applicator of my new design.

FIG. 20 is a front view of the fourth embodiment of the applicator of my new design.

FIG. 21 is a right side view of the fourth embodiment of the applicator of my new design. The left side view is a mirror image of FIG. 21.

FIG. 22 is a rear view of the fourth embodiment of the applicator of my new design.

FIG. 23 is a top view of the fourth embodiment of the applicator of my new design; and,

FIG. 24 is a bottom view of the fourth embodiment of the applicator of my new design.

The cord member being shown fragmented for ease of illustration.

UNITED STATES PATENT AND TRADEMARK OFFICE
CERTIFICATE OF CORRECTION

PATENT NO. : Des. 536,450 S
APPLICATION NO. : 29/192463
DATED : February 6, 2007
INVENTOR(S) : Bradley Peter Ryan

Page 1 of 1

It is certified that error appears in the above-identified patent and that said Letters Patent is hereby corrected as shown below:

On the title page please correct the name of Item (73) assignee "Encore Medical Alert Corporation" to read --Encore Medical Asset Corporation--

Signed and Sealed this

Tenth Day of April, 2007

A handwritten signature in black ink, appearing to read "Jon W. Dudas". The signature is written in a cursive style with a large, stylized "J" and "W".

JON W. DUDAS
Director of the United States Patent and Trademark Office
